Primary Examiner — Rebekah A Caruso**CLAIM**

The ornamental design for a smartwatch, as shown and described.

DESCRIPTION

FIG. 1 is a front, right and top side perspective view of a smartwatch showing our new design;

FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of FIG. 1; and,

FIG. 10 is a partial enlarged view of FIG. 2.

The broken lines shown in the drawings represent portions of the smartwatch that form no part of the claimed design.
